UNITED STATES PATENT OFFICE.

JOHN E. GLIDDEN, INSANE, OF BEVERLY, MASSACHUSETTS, BY SADIE E. GLIDDEN, GUARDIAN, OF BEVERLY, MASSACHUSETTS; SAID SADIE E. GLIDDEN, ADMINISTRATRIX OF SAID JOHN E. GLIDDEN, DECEASED, ASSIGNOR TO UNITED SHOE MACHINERY COMPANY, OF PATERSON, NEW JERSEY, A CORPORATION OF NEW JERSEY.

HEEL-DIE.

1,086,158.

Specification of Letters Patent. Patented Feb. 3, 1914.

Application filed March 13, 1911. Serial No. 614,156.

To all whom it may concern:

Be it known that JOHN E. GLIDDEN, of Beverly, in the county of Essex and State of Massachusetts, insane, invented certain 5 Improvements in Heel-Dies, of which the following description, in connection with the accompanying drawings, is a specification, like reference characters on the drawings indicating like parts in the several figures.

10 This invention relates to dies for building heels, and more particularly to dies for cutting out lifts and parts of lifts from pieces of leather or the like, the dies serving as receptacles into which the died-out pieces 15 are pressed and in which these pieces are compactly arranged to form heels for boots and shoes.

15 Dies of the type to which this invention particularly relates are known commercially as Haverhill heel dies. These dies are usually fixed upon a bench or table with their cutting edges extending upwardly therefrom, and in practice the pieces of 20 leather to be cut are laid upon the cutting edge of the die and then died-out by being forced downwardly against the cutting edge by a mallet or other similar hand operated instrument. Waste scraps of leather of 25 irregular form and of varying sizes and shapes are utilized, such, for example, as are left from the operations of dieing out soles, heel lifts and the like from sides of leather. When enough sections of leather 30 have been cut and compactly forced down into the die to fill it completely, one or more heel nails are driven to hold the different sections of the heel firmly together. Before the built-up heel is compressed it is 35 frequently provided with a whole or one piece heel seat lift of leather or of leather board and afterward, during the heelng operation, a whole outer or top lift is usually blind nailed thereto, these one piece 40 lifts assisting materially in holding the intermediate sections of scrap leather securely in place. In certain classes of work, however, it is desirable to have the finished heel present similarly inclined breast and rear 45 faces, the breast slope being usually inwardly and rearwardly, and the pitch at the back being outwardly and rearwardly 50 from the outer lift to the heel seat. Ac-

cordingly a principal object of this invention is to provide a die of the character described by the use of which an undercut or inwardly inclined heel breast can be secured and at the same time a similar slope can be given to the back of the heel. 55

In the embodiment of this invention herein shown and described in connection with a die of the type above mentioned, this and other objects and advantages hereinafter set forth, are attained by inclining or tipping both the rear and breast walls of the die, the 60 slope of the front or breast wall being preferably in the same direction as that of the rear wall. By so inclining the breast and rear walls of the die, particularly if the angle of inclination at the rear be substantially equal to that at the front, heels can be built up by superposing lifts of substantially the same area and the desired pitch at back and front can be obtained, the successive lifts being displaced toward the rear 65 relatively to each other as the building operation progresses. In order that the breast slope thus obtained may not be destroyed in the compressing operation as would be the case if a vertical breast plate were employed, 70 a heel having inclined breast and rear surfaces may be compressed in a mold having an inclined breast plate, such, for example, as that described in United States Letters Patent to Lund No. 974,405, dated November 1, 1910, in which case the breast slope 75 will be unimpaired by the compressing operation. 80

A further feature of the present invention consists in the resulting economy of stock 85 effected by its use in producing certain kinds of heels, particularly those intended to have permanently inclined breast faces. While it is possible in the breastng operating to incline the breast face similarly to the pitch 90 of the rear, it is much more economical so to build and compress the heel that, prior to the breastng, the contour of the heel may approximate as closely as possible its finished form, in order to reduce the amount 100 of waste stock removed in breastng. From the front or breast edge of the heel seat to the breast edge of the outer lift the slope will be practically that desired in the finished heel and hence there will be a minimum 105 of waste to be removed by the breaster.

Indeed, in cheap grades of work a very satisfactory breast can be obtained merely through the compressing operation without any breasting whatever, provided the heel is built and compressed with its breast face presenting substantially the contour desired for the finished heel. Preferably the angle of inclination of the front of the die will be substantially the same as the angle of inclination of the rear, since this construction gives the best results in obtaining properly directed and sufficient pressure to effect the desired rear pitch and because in finished heels which present a final slope it is usually desired that the breast pitch shall closely approximate the rear pitch, both in direction and in extent.

Another feature of the construction contemplated by this invention results from the fact that the tilt of the die giving to its cutting edge an oblique cut through the superposed leather largely diminishes the resistance of the leather to the die. This not only facilitates the cutting, but also tends to leave the cut edges of the leather clean and free from outstanding ragged fringes. Moreover, the oblique cut prolongs the life of the die by lessening the liability of breakage, particularly at weak points such as the corners between the curved edge and the straight edge where experience has shown that the die is most liable to break down and by insuring that the cutting edge of the die will not be so frequently and easily dulled.

These and other features will appear from the following description of a preferred embodiment of this invention read in connection with the accompanying drawings.

Referring to the drawings: Figure 1 is a view in perspective of a die in which the present invention is embodied. Fig. 2 is a view in perspective of a heel built up by the use of the die shown in Fig. 1. Fig. 3 is a longitudinal vertical central section of the die shown in Fig. 1 but on a smaller scale.

The heel die in connection with which one embodiment of this invention is shown for purposes of illustration has a base 2 provided with recesses 4 adapted to receive clamping bolts for removably securing the die as desired to a table or bench. Lugs 6 upstanding from the base 2 and conveniently cast integral therewith, are threaded at 8 to receive screw threaded bolts 10, the bolts 10 bearing against opposite sides of the body portion of the die and securing the die in position on the base 2. The die comprises a hollow body portion which consists of a wall 12 upstanding from the base and an ejector 14 which, as shown, is a paddle loosely fitting the interior of the die and provided with a handle 16 arranged

to project outwardly through a slot 18 in the front of the upstanding wall 12. The under side of the paddle 14 has a thickened portion which rests normally upon the base plate 2. This paddle 14 normally serves as a bottom plate for the die on which the heel seat face of the heel is formed but it is arranged to be raised by means of the handle 16 to eject the built up heel from the die when desired. The wall 12 is formed with a straight front or breast face 20 and a U-shaped or curved rear portion 22, and has its upper edge 24 sharpened for cutting.

It will be observed by reference to Fig. 1 that in accordance with the present invention, the wall 12 is inclined forwardly at the front and at the rear so that the front face 20 of the wall 12 and the rear portion 22 are both tipped forwardly and so that the wall 12 at the rear overhangs a portion of the base plate 2 with the result that the built up heel shown in Fig. 2, in which 26 represents the outer face of the heel to which the outer or top lift is to be attached and 28 and 30 the breast and rear faces respectively, will have its breast and rear faces sloping rearwardly and inwardly from the outer lift to the heel seat, and so that the pitch of the rear 30 will extend in the same direction as the slope of the breast 28.

As shown in Fig. 1, and as above suggested, the die is conveniently made with the angle of inclination of the rear portion 22 of the wall 12 substantially the same as the angle of inclination of the front or breast wall 20, with the result that the different layers or lifts are of approximately the same area, this arrangement being both commercially desirable and productive of economy of time and of stock in cutting out the lifts or parts of lifts.

It should be noticed that although preferably the die will be constructed with its wall forwardly inclined it could equally well and entirely within the spirit and scope of this invention be made with its wall backwardly inclined, in which case, of course, the process of building the heel would be exactly reversed, that is, the heel would be built up with its top or outer portion 26 formed on the ejector 18 and its heel seat face at the top of the die. Or and equally within the invention, the die could be formed with the angle of inclination of its front face different from that of the rear face. Various other modifications such as would readily occur to those skilled in the art could be made without departing from the present invention as shown and described herein purely by way of illustration and not by way of limitation.

In operation, the workman selects from a miscellaneous assortment of scraps of sole leather and the like such pieces as will cut to advantage, holds the selected pieces over

the cutting edge of the die or over a portion thereof, and forces the leather down over the die by means of blows of the mallet, continuing this mode of operation until the die 5 is filled up and using the mallet to hammer down the stock compactly so as to form a firm and well knit heel. As the leather sections are forced downwardly into the die by reason of the slope of the breast wall 20, and 10 the inclination of the rear wall 22 there will be a crowding rearwardly so as to exert a sufficient compression to effect the desired pitch of the rear as above explained. When the heel has thus been built up in the die, a 15 number of heel nails are driven through at various points as above explained, and the heel is then ejected from the die, the operator commonly hitting the handle 16 of the ejector 14 a sharp blow with the mallet 20 thereby raising the paddle 14 to eject the heel.

Having now fully described the present invention as preferably embodied in one illustrative construction, what is claimed as 25 new and desired to be secured by Letters Patent of the United States is:—

1. A heel building die having an upstanding wall formed with front and rear portions obliquely inclined from the horizontal 30 in the same direction, the said wall being provided with an upwardly extending cutting edge.

2. A die for building heels having inclined breast and rear surfaces, said die 35 having an upstanding wall provided with an inclined rear portion formed to project over a part of the interior of the die, and a forwardly inclined front portion, said wall having an upwardly extending cutting edge.

40 3. A heel building die having an upstanding wall formed with a U-shaped portion at the rear and a straight portion at the breast, both said portions being inclined forwardly whereby successive lifts are displaced to-

ward the rear relatively to each other as the 45 building operation progresses.

4. A heel building die having an upstanding wall with an upwardly extending cutting edge and formed with forwardly inclined rear and breast faces, the angle of inclination of the rear face being substantially 50 equal to the angle of inclination of the breast face.

5. A heel building die having an upstanding wall curved at the rear and straight at 55 the breast, said wall having its rear and breast faces both inclined in the same direction.

6. A heel building die having an upstanding wall, U-shaped at the rear and straight 60 at the breast, and a heel seat plate constituting the bottom of the die, said wall having both its rear and breast faces inclined obliquely to the plane of said heel seat plate.

7. A heel building die comprising an upstanding wall having rear and breast faces both inclined in the same direction and at substantially the same angle to permit a heel with inclined rear and breast surfaces 70 to be built up therein by superposing lifts of substantially the same area.

8. In a die for building pieced heels the combination of an upstanding wall provided with a cutting edge and having rear and 75 breast faces both inclined in the same direction, a bottom plate normally constituting the bottom of the die, and means for raising said plate when desired to eject the built up heel from the die.

In testimony whereof I have signed my name to this specification in the presence of two subscribing witnesses.
